ATTORNEYS

UNITED STATES PATENT OFFICE.

WILLIAM W. LEAK, OF MONTGOMERY, ALABAMA.

PLOW.

SPECIFICATION forming part of Letters Patent No. 402,253, dated April 30, 1889.

Application filed November 30, 1888. Serial No. 292,339. (No model.)

To all whom it may concern:-

Be it known that I, WILLIAM W. LEAK, of 5
Montgomery, in the county of Montgomery
and State of Alabama, have invented a new
and useful Improvement in Plows, of which
the following is a specification.

My invention is an improvement in that
class of devices which seek to avoid the re-
sharpening of plows by providing plates thin
10 enough to form an edge for the plow and
adapted to be adjusted down on the body of
the plow-point as the plate is worn away.

The present invention consists in the novel
construction of the improved point, as will be
15 described and claimed.

In the drawings, Figure 1 is a plan view of
a plow-sweep provided with my improvement.
Fig. 2 is a sectional view thereof on about line
20 xx , Fig. 1; and Fig. 3 is a detail perspective
view of the improved point.

The point B, constituting my invention, is
formed of thin metal, in approximately V
shape, with its wings 1 1 diverging from the
forward end or point, where said wings are
25 joined. This point B is provided with slots
b, adapted to permit the passage of the fast-
ening-screws C, by which the point B is se-
cured to the sweep A. It will be seen that
these slots b are formed at the juncture and
30 near the free ends of the wings 1 and in line
or parallel with a line intersecting the angle
between the said wings, as will be fully un-
derstood from Figs. 1 and 3.

Where desired, washers D may be provided
35 on the screws C, to receive the bearing of the
nuts turned on said screws.

The sweep A, it will be seen from the draw-
ings, inclines downward on opposite sides from
a central longitudinal line, being made of a
40 transverse sectional shape, somewhat in the
form of an inverted V. The point B, being
conformed to such sweep A, has its wings 1 1
formed to diverge not only from their junct-
ure at their forward ends rearwardly, but
45 also transversely, such transverse or lateral

divergence conforming in angle to that of the
opposite wings of the sweep A. The said point
B may therefore be said to have its wings
formed to diverge laterally as well as longi-
tudinally. The invention is simple, and, so 50
far as I am aware, distinguished from all prior
devices for the same purpose in the construc-
tion of the point B with wings 1 1 arranged
to diverge both longitudinally and laterally
or transversely, and provided with slots at 55
the juncture of and near the ends of such
wings, such slots being arranged parallel with
each other and with a line intersecting the
angle between the wings.

Having thus described my invention, what I 60
claim as new is—

1. As an improved article of manufacture,
the plow-point B, consisting of a thin plate of
metal formed approximately V-shaped, with
wings 1 1, such wings being arranged to di- 65
verge longitudinally and laterally or trans-
versely, and provided with slots at the junct-
ure of and near the outer ends of wings 1,
such slots being arranged parallel with each
other and with a line intersecting the angle 70
between the wings, all substantially as and
for the purposes set forth.

2. The combination, substantially as herein
described, of the sweep A, constructed to in-
cline downward on opposite sides from a cen- 75
tral longitudinal line, the point B conformed
to such sweep and consisting of a thin V-
shaped metal plate having wings 1 1 arranged
to diverge longitudinally and laterally or
transversely, and provided at its center and 80
near its ends with the slots b, and the fasten-
ing-bolts passed through such slots and
through openings in the point A and secured,
all substantially as and for the purposes set
forth.

WILLIAM W. LEAK.
